UNITED STATES PATENT OFFICE

154,572

DESIGN FOR A LADY'S HANDBAG

Fred B. Taccia, Boston, Mass., assignor to Colt-Cromwell Company, Inc., Boston, Mass., a corporation of New York

Application December 14, 1948, Serial No. 150,153

Term of patent 3½ years

(Cl. D87—3)

To all whom it may concern:

Be it known that I, Fred B. Taccia, a citizen of the United States of America, residing at Boston, in the county of Suffolk and Commonwealth of Massachusetts, have invented a new, original, and ornamental Design for Lady's Handbag, of which the following is a specification, reference being had to the accompanying drawing, forming part thereof.

Fig. 1 is a front elevation of a lady's handbag, showing my new design, the flap of the bag being closed;

Fig. 2 is a view similar to Fig. 1, showing the flap in opened position;

Fig. 3 is a side elevation looking to the left of Fig. 1; and

Fig. 4 is a rear elevation of the bag.

I claim:

The ornamental design for a lady's handbag, as shown.

FRED B. TACCIA.
